UNITED STATES PATENT OFFICE.

LINDSLEY SCHEPMOES, OF NEW YORK, N. Y., ASSIGNOR TO THE
SAFETY CAR HEATING & LIGHTING COMPANY, A CORPORA-
TION OF NEW JERSEY.

DESIGN FOR A LAMP-CASE.

No. 37,966.

Specification for Design.

Patented April 24, 1906.

Application filed February 23, 1906. Serial No. 302,641. Term of patent 14 years.

To all whom it may concern:

Be it known that I, LINDSLEY SCHEPMOES, a citizen of the United States, residing at New York city, in the county of New York, State of New York, have invented a new, original, and ornamental Design for a Lamp-Case, of which the following is a specification, reference being had to the accompanying drawings, forming a part thereof.

Figure 1 is a front elevation of the lamp-

case, showing my new design. Fig. 2 is a side elevation of the same.

I claim—

The ornamental design for a lamp-case as shown.

LINDSLEY SCHEPMOES.
